(57) **CLAIM**

The ornamental design for a pruner, as shown and described.

DESCRIPTION

FIG. 1 is a left side view of a pruner of the claimed design. FIG. 2 is a right side view of a pruner of the claimed design.

FIG. 3 is a top view of a pruner of the claimed design.

FIG. 4 is a bottom view of a pruner of the claimed design.

FIG. 5 is a front view of a pruner of the claimed design.

FIG. 6 is a back view of a pruner of the claimed design.

FIG. 7 is a left perspective of a pruner of the claimed design; and,

FIG. 8 is a left perspective of a pruner of the claimed design. The broken line showing of the pruner is included for the purpose of showing portions of the pruner and forms no part of the claimed design.
